UNITED STATES PATENT OFFICE.

WILFORD E. BURNS, OF SAN FRANCISCO, CALIFORNIA, ASSIGNOR TO MAX J. BRANDENSTEIN, MANFRED BRANDENSTEIN, AND EDWARD BRANDENSTEIN, OF SAN FRANCISCO, CALIFORNIA, A FIRM DOING BUSINESS AS M. J. BRANDENSTEIN & CO.

CAN-TESTING MACHINE.

1,378,215.

Specification of Letters Patent. Patented May 17, 1921.

Application filed January 31, 1920. Serial No. 355,362.

To all whom it may concern:

Be it known that I, WILFORD E. BURNS, a citizen of the United States, and a resident of the city and county of San Francisco and State of California, have invented a new and useful Can-Testing Machine, of which the following is a specification.

My invention relates to apparatus for testing the tightness of the joints in a can. 10 An object of the invention is to provide a machine for determining whether or not, the joints of cans are tight, before the contents of the cans are placed in them.

The invention possesses other objects and 15 features of advantage, some of which, with the foregoing will be set forth in the following description of the preferred form of my invention which is illustrated in the drawings accompanying and forming part 20 of the specification. It is to be understood that I do not limit myself to the showing made by the said drawings and description, as I may adopt variations of the preferred form within the scope of my invention as 25 set forth in the claims.

Referring to the drawings:

Figure 1 is a vertical sectional view through the middle of the machine. Fig. 2 is a vertical sectional view through the 30 middle of the machine, the plane of section being at right angles to that of Fig. 1. Fig. 3 is a side elevation of the machine. Fig. 4 is a vertical sectional view on a larger scale of the upper portion of the machine. Fig. 35 5 is an elevation, partly in diagram of the automatic switch forming part of the mechanism.

Before the contents are placed in metallic containers it is desirable to ascertain if the 40 seamed and soldered joints of the containers are perfectly tight, so that defective containers may be rejected. In general terms, the testing machine of my invention comprises a tank adapted to contain water, a carriage into which the can to be tested may be thrust by the operator, means for lowering the carriage into the tank to immerse the can, a reservoir of air under pressure, means acting automatically and in time 45 with the downward movement of the carriage for closing the filling opening in the can and connecting the can with the air reservoir so that prior to immersion there is a pressure within the can greater

than the maximum pressure exerted on the 55 can by the water, means for automatically lighting the tank from below so that the operator can see bubbles arising from a defective can and means acting in time with the lifting of the carriage for allowing the 60 air under pressure to exhaust from the can.

My testing machine comprises a tank 2 inclosed and supported in a suitable frame 3, vertical side members 4 of which, extend upwardly to provide a mounting for the operating mechanism. On cross beams 6 and 7, and directly over the center of the tank is arranged a cylinder 8 set in suitable heads 9 and 11. A rod 12 fitted with piston 13 is slidably mounted in the cylinder, the rod 65 projecting from the cylinder through a stuffing box 14 in the lower head 9. A valve box 16 is fixed on one of the side members 4, and is formed with an air chamber 17 in which a slide valve 18 is adapted to 70 be reciprocated to cover or uncover passages 19 and 21. The air chamber is connected with a suitable source of air under pressure of, say, 65 lbs., by the pipe 22, and a pipe 75 23 connects passage 19 with passage 24 80 formed in the cylinder head 11 and opening into the cylinder above the piston. A pipe 26 connects the passage 21 to the passage 27 formed in the lower cylinder head and opening into the cylinder below the piston. 85 The valve box is also provided with an exhaust passage 28 connecting the air chamber 17 with the passage 29 which passes through the valve box and opens at both ends into the atmosphere. Thus, by movement of the 90 slide valve 18 upwardly, air under pressure is admitted below the piston 13 to drive it upwardly in the cylinder, and a passage opened to allow the air above the piston to escape. Downward movement of the 95 slide valve opens the passage for the air below the piston to escape and at the same time connects the proper passages to allow air under pressure to enter the cylinder above the piston to impel it downwardly. 100

The valve rod 31 is fixed at its outer end to the slide 32, slidably mounted in a bracket 33 fixed on the frame 4. The lower end of the slide is pivotally connected to the rod 34, pivoted to the control lever 36 pivoted 105 on the frame. The control lever is formed with handles 37, one at each extremity, and provides means whereby an operator on

either side of the machine may manually initiate the action of the apparatus.

Fixed on the lower end of the piston rod 12 is the carriage in which the can to be tested is placed. The carriage comprises two square hoops 38 connected on the inside by slats 39 within which the can 41, shown in dotted lines in Fig. 1 is placed. Cross bars 42 connect the lower portions of the hoops 38 and form a bracket on the ends of which plates 43 and 44 are pivoted by means of arms 46 integral with each plate. Flanged wheels 47 are rotatably mounted on the plates 43 and 44 and are adapted to form a rolling engagement with tracks 48 vertically disposed on the inside of the tank. The position and proportion of the parts is such that when the carriage is in its upper position, the wheels rest on the upper end 15 of the tracks, supporting the plates as shown in Fig. 1. In this position the plates form platforms or rests of use in facilitating the placing of the cans in and withdrawing them from the carriage. As the carriage is lowered into the tank, the engagement of the rollers with the track forces the plates into a vertical position as shown in the dotted lines near the bottom of Fig. 1 holding the can securely in the carriage. The 20 plate 43 is provided with a passage 49 connected by flexible hose 51 with pipe 52 fixedly held in the arm 53 projecting from the carriage and slidably mounted in the cross beams 6 and 7. The top of the pipe is connected by flexible conductor 54 with a source of air under low pressure, say about 12 pounds. Conveniently such low pressure air may be taken from the high pressure tank through a reducing valve of known 25 structure. The opening of the passage 49 upon the face of the plate 43 is surrounded by a gasket 56 adapted, when the plate rises to vertical position, to engage about the filling neck 57 of the can and establish a sealed connection between the can and the 30 low pressure air conductors. This connection is established immediately following the initial downward movement of the carriage and is maintained until the carriage is again near the upper position.

Means are provided for closing the low pressure conductors to the passage of air while the carriage is in and adjacent to its upper position, and for opening the conductors to the passage of air to create a pressure within the can just prior to its immersion and continuing until it is about to leave the water. A valve 61, Fig. 4, with vent 62 into the atmosphere is arranged in the pipe 52 and is adapted to be moved by a lever including two spring pressed fingers 63 and 64. Stops 66 and 67 are arranged on the side frame member 4 for actuating the valve as follows: In the position of parts 35 shown in Fig. 2, the valve is closed, the pas-

sage below the valve being in communication with the atmosphere through the vent 62. Shortly following the beginning of the downward stroke of the carriage, it being remembered that the pipe 52 is fixed to the carriage and moves with it, the finger 63 engages the stop 66, operating the valve to close the vent and open a passage to permit air to flow through the conductors into the can, the engagement of the gasket 56 with the filling neck of the can having just previously occurred. As the carriage and pipe 52 near the bottom of their stroke the spring pressed finger 64 which is now on the outside snaps past the stop 67, but on the upstroke 40 is operated by the stop to close the valve and open, through the vent 62, communication between the conductors below the valve and the atmosphere. By the time the plate 43 falls and uncovers the filling opening of 45 the can the air pressure in the can has dropped to about that of the atmosphere, whatever air under pressure there is in the can at this time escaping through the uncovered filling opening. Near the end of 50 the upward stroke the finger 63 snaps past the stop 66, and the parts are again in the first position as shown in Fig. 2.

Means are provided for cushioning the stroke at both ends so that the carriage is 55 brought to rest quietly and without jar or noise in both upper and lower positions. Slidably mounted in bearings on the cross beams 6 and 7 is a rod 68. The upper bearing comprises blocks 69 resiliently 60 interposed between the blocks and the bolt 72 passing through the blocks and the housing 73. Thus a regulable frictional resistance to the sliding of the rod 65 is provided which prevents movement of the rod except as actuated by superior force. Arms 74 and 76 are fixed on the rod, and are provided with apertures through which the pipe 52 loosely passes. The position of the arms is such that near 70 the end of the upward stroke of the carriage and pipe 52 the upper end of the valve 61 engages the arm 74 and carries the rod 68 upwardly a short distance. Near the 75 end of the downward stroke, the lower arm 76 is engaged by the lower end of the valve or by a collar 77 fixed on the pipe 52 and the rod 68 is carried downwardly a short distance. Mounted for pivotal movement 80 on the slide 32 is a lever arm 78, pivotally connected at one end with the rod 68, and at the other end with a rod 79, to which is fixed a plunger 81 loosely fitting the passage 29 through which, it will be remembered, the exhaust from the cylinder 8 is 85 discharged. When the lever 36 is moved to lower the slide valve 18, to allow air under pressure to enter the top of the cylinder 8 the lever 78 pivots about its connec- 90

- tion on the rod 68 and pulls down the plunger 81 to leave a clear exhaust passage 21—28—29. As the main piston 13 nears the end of its downward stroke, the collar 5 77 engages the arm 76, and moves the rod 68 downwardly. The arm 78 then pivots about its connection on the slide 32, moving the plunger 81 upwardly to cover the exhaust passage 28. The remaining air under 10 the piston 13 and in the passages is thus trapped, slowly escaping past the loosely fitting plunger 81, and cushioning the end of the stroke. When the lever 36 is moved to initiate the upward stroke of the piston 15 13, the lever 78 is actuated to push up the plunger 81 above the outer opening of the passage 28, and then, near the end of the upward stroke, with movement of the rod 68, is actuated to pull down the plunger 81 20 to trap the air escaping from the upper end of the cylinder 8, cushioning the end of the stroke as before.

Means are provided for illuminating the tank during the immersion of the can so 25 that the operator can more clearly see the bubbles arising from a defective can. A glass plate 82 is arranged in the bottom of the tank and an electric lamp 83 suitably mounted within a reflector 84 arranged below the plate so that the light rays are thrown upwardly through the water of the tank. The lamp is connected in series to circuit 86, one side of the circuit being connected to the power line 87, and the other 30 side of the power line and the other side of circuit 86 being connected to spaced contact ribs 88 arranged on and insulated from the frame member 4 in position to be engaged by contact 89 mounted on and insulated from the collar 77. Near the end of the downward stroke of the carriage the contact 89 engages between the ribs 88, closing the circuit 86 therethrough and lighting the lamp until the contact leaves the ribs 35 on the upward stroke of the carriage.

I claim:

1. A can testing machine comprising a tank, a carriage for the can to be tested, means for lowering and raising said carriage 50 into and out of said tank, and means operated by said carriage during its downward movement for introducing into the can in said carriage air under pressure.

2. A can testing machine comprising a tank, a carriage for the can to be tested, means for lowering and raising said carriage into and out of said tank, a conductor for air under pressure, a valve in said conductor and means operated automatically during the 55 downward movement of said carriage for establishing a connection between said conductor and said can and for turning said valve to permit air under pressure to fill said can.

3. A can testing machine comprising a

tank, a carriage for the can to be tested, means for lowering and raising said carriage into and out of said tank, and means operated automatically during the downward movement of said carriage for introducing 70 into the can in said carriage air under pressure, and during the upward movement of said carriage for releasing the pressure in said can.

4. A can testing machine comprising a 75 tank adapted to contain a quantity of liquid, a carriage for the can to be tested, means for moving the carriage to immerse the can in the liquid and to lift the can above the liquid, and automatically operated means for 80 maintaining air under pressure within the can during the period of immersion.

5. A can testing machine comprising a tank adapted to contain a quantity of liquid, a carriage for the can to be tested, means for 85 moving the carriage to immerse the can in the liquid and to lift the can above the liquid, automatically operated means for maintaining air under pressure within the can during the period of immersion and means for 90 illuminating the liquid in the tank during the period of immersion.

6. A can testing machine comprising a tank adapted to contain a quantity of liquid, a carriage for the can to be tested, means for 95 moving the carriage to immerse the can in the liquid, a plate pivoted to said carriage and having a passage therein adapted to be registered with the filling opening of said can, a conductor for air under pressure connected to said plate and opening into said passage, a valve in said conductor, means for moving said plate to register said passage with said filling opening prior to the period of immersion, and means for opening said 100 valve to permit air under pressure to fill said can subsequent to the movement of said plate.

7. A can testing machine comprising a tank, a carriage for the can to be tested, means for lowering and raising said carriage 110 into and out of said tank, a plate pivoted to said carriage and having a passage therein adapted to be registered with the filling opening of said can, and a cam track arranged to move said plate to register said 115 passage with said filling opening during the downward movement of said carriage.

8. A can testing machine comprising a tank, a carriage for the can to be tested, means for lowering and raising said carriage 120 into and out of said tank, a plate pivoted to said carriage and having a passage therein adapted to be registered with the filling opening of said can, a cam track arranged to move said plate to register said 125 passage with said filling opening during the downward movement of said carriage, and means for introducing air under pressure into said passage during the period of such registration.

9. A can testing machine comprising a tank, a carriage for the can to be tested, means for lowering and raising said carriage into and out of said tank, a plate pivoted to said carriage and having a passage therein adapted to be registered with the filling opening of said can, a second plate pivoted to said carriage and adapted to engage the opposite end of said can, said plates forming loading and unloading platforms for said carriage in its upper position, means operative with the downward movement of said carriage for moving said plates into engagement with said can, and means for introducing air under pressure into said passage to fill said can during said downward movement.
10. A can testing machine comprising a tank, a carriage for the can to be tested, means for lowering and raising said carriage into and out of said tank, a plate pivoted to said carriage and having a passage therein adapted to be registered with the filling opening of said can, a second plate pivoted to said carriage and adapted to engage the opposite end of said can, said plates forming loading and unloading platforms for said carriage in its upper position, a cam track arranged to move each plate into engagement with said cam during the downward movement of said carriage, a conductor for air under pressure connected to said first plate and opening into said passage, and means operated during the downward movement of the carriage for permitting air to flow through said conductor into said can and during the upward movement of the carriage for permitting said air to escape from said can.
11. A can testing machine, comprising a tank adapted to contain a liquid, a carriage for the can to be tested, a cylinder, a piston and piston rod in said cylinder and connected to said carriage, manually controlled means for admitting air under pressure into one end of said cylinder to move said carriage into said tank, automatically operating means for trapping air in the opposite end of the cylinder to cushion the end of the stroke, and means for introducing air under pressure into said can during said stroke.
12. A can testing machine, comprising a tank adapted to contain a liquid, a carriage for the can to be tested, a cylinder, a piston and piston rod in said cylinder and connected to said carriage, manually controlled means for admitting air under pressure into one end of said cylinder to move said carriage into said tank, means for cushioning the end of the stroke, and means for introducing air under pressure into said can during said stroke.
13. A can testing machine, comprising a tank adapted to contain a liquid, a carriage for the can to be tested, a cylinder, a piston and piston rod in said cylinder and connected to said carriage, manually controlled means for admitting air under pressure into one end of said cylinder to move said carriage into said tank, means for cushioning the end of the stroke, a plate pivoted to said carriage and having a passage therein adapted to be registered with the filling opening of said can, a second plate pivoted to said carriage and adapted to engage the opposite end of said can, said plates forming loading and unloading platforms for said carriage in its upper position, means operative with the downward movement of said carriage for moving said plates into engagement with said can, and means for introducing air under pressure into said passage to fill said can during said downward movement.
14. A control mechanism for a fluid pressure operated piston comprising a cylinder in which said piston slides, a valve box formed with an air chamber therein, means for introducing air under pressure into said air chamber, means providing a passage from each end of the cylinder to said air chamber, means providing an exhaust passage from said air chamber, a valve in said air chamber movable to uncover either passage to said cylinder and to place the other passage in communication with said exhaust passage, a manually controlled slide for moving said valve, a lever pivoted on said slide, means for blocking said exhaust passage connected to one end of said lever and normally lying to one side of said passage, and means operating in time with the movement of said piston for moving said lever about its pivot on said slide to move said blocking means across said exhaust passage.
15. A control mechanism for a fluid pressure operated piston comprising a cylinder in which said piston slides, a valve box formed with an air chamber therein, means for introducing air under pressure into said air chamber, means providing a passage from each end of the cylinder to said air chamber, means providing an exhaust passage from said air chamber, a valve in said air chamber movable to uncover either passage to said cylinder and to place the other passage in communication with said exhaust passage, a slide for moving said valve, a lever pivoted on said slide, means for blocking said exhaust passage connected to one end of said lever and normally lying to one side of said passage, a rod slidably arranged adjacent said cylinder and pivotally connected to the other end of said lever, and means for moving said rod with said piston near the end of each stroke to turn said lever about its pivot on said slide to move said blocking means across said exhaust passage.
16. A control mechanism for a fluid pressure operated piston comprising a cylinder in which said piston slides, a valve box formed with an air chamber therein, means

for introducing air under pressure into said air chamber, means providing a passage from each end of the cylinder to said air chamber, means providing an exhaust passage from said air chamber, a valve in said air chamber movable to uncover either passage to said cylinder and to place the other passage in communication with said exhaust passage, a slide for moving said valve, a lever pivoted on said slide, means for blocking said exhaust passage connected to one end of said lever and normally lying to one side of said passage, a rod slidably arranged adjacent said cylinder and pivotally connected to the other end of said lever, means for moving said rod with said piston near

the end of each stroke to turn said lever about its pivot on said slide to move said blocking means across said exhaust passage, and manually controlled means for moving 20 said slide to operate said valve and to move said lever about its pivot on said rod to move said blocking means clear of said exhaust passage.

In testimony whereof, I have hereunto set 25 my hand at San Francisco, California, this 21st day of January 1920.

WILFORD E. BURNS.
